LAG FUSE

Gordon F. Laing, Delavan, Wis., assignor to Economy Fuse and Manufacturing Co., Chicago, Ill., a corporation of Illinois

Application April 16, 1952; Serial No. 282,603

10 Claims. (Cl. 200—123)

1

This invention relates to fuses of the dual element type, which combine both instantaneous and lag fuse elements arranged in series.

It is directed in general toward the type of fuse shown in my United States Patent No. 2,613,297, issued on October 7, 1952; and in an application made of even date herewith in the names of Gordon F. Laing and Gustav Rensner, Serial No. 282,601.

In both of these fuse constructions, the lag elements are actuated after an interval of time during which current over-load less than that amount required to blow the instantaneous fuses increases the resident heat of the lag elements up to the temperature required to fuse the eutectic solder by which they are held in closed circuit position. The actuation of the elements from closed to open circuit position is effected by a tension spring arranged to pull the elements out of engagement once the solder fuses to make this possible.

In the present invention, the lag elements are forced into open position by a pushing action exerted upon one of them by a spring-actuated insulating member which pushes a moving circuit-carrying part from closed circuit to open circuit position, and holds it there in a positive manner.

Fuses constructed in accordance herewith are characterized by their simplicity of construction and reduced number of parts, and have the advantage over other constructions in that there is always a member bridging the space between opposed lag elements which is either conductive or insulative, depending upon the closed or open condition of the circuit.

Reference will now be made to the accompanying drawings, in which—

Figure 1 is a plan view showing a fuse according to the present invention in closed circuit condition, with some of the parts in section;

Figure 2 is a mid-sectional elevation of the construction shown in Figure 1 and taken at substantially a 90-degree position from the latter view;

Figure 3 is a view corresponding to Figure 2, showing the parts in open circuit position.

Referring now more particularly to the drawings, there is provided the usual insulating fiber or plastic casing 10, which has terminal caps 12 and 14 disposed to close the opposite ends thereof. Diaphragms 16 and 18 divide the casing into three chambers, in the end ones of which are positioned links 20 and 22 which extend from the terminals 12 and 14 through the diaphragms 16 and 18 into the central chamber, where they

connect with spaced massive metallic conductor members 24 and 26, respectively. As shown in Figures 2 and 3, these members are bored coaxially at 28 and 30, respectively, and in the case of the element 24 a countersink 32 is provided in the end wall thereof in relation to its bore 28. Within the latter there is confined an expansion spring 34, against which an insulative bridging plunger 36 is disposed. In the opposing massive member 26, a metallic plunger 38 is disposed in its bore 30, which plunger has a contact head 40 secured thereto, which is adapted to seat within the countersink 32 of the opposing member 24.

In the closed circuit position, the metallic plunger 38 is caused to bridge the space between the massive members 24 and 26 to cause its contact head 40 to engage in the countersink 32, where it is held by eutectic solder 42 applied at several points as indicated. When the metallic plunger 38 is thus positioned to close the circuit, the insulative plunger 36 is forced into the bore 28 against the resistance to compression of the spring 34. Let it be assumed that current representing an overload of insufficient magnitude to cause the fuse links 20 and 22 to burn out is passed through the parts arranged as shown in Figures 1 and 2: the massive members 24 and 26 commence gradually to heat until a temperature is attained that is in excess of the melting point of the eutectic solder 42. The solder then melts to release the metallic plunger 38, which is caused to come into open circuit position by the action of the spring 34 against the insulative plunger 36. This latter pushes the metallic plunger into open circuit position, as shown in Figure 3, and holds it in that position in a positive manner.

It will be seen from the foregoing description that when the fuse is in closed circuit position, the metallic plunger 38 bridges the space between the massive metallic conductors 24 and 26, and when its parts are in open circuit position, as shown in Figure 3, the insulative plunger 36 bridges the space between these massive members; so that at first the insulative plunger is displaced by the metallic plunger, and then the metallic plunger is displaced by the insulative plunger.

The end chambers, in which the links 20 and 22 are accommodated, may be filled with quenching powder 23, as is well known to the art.

I claim:

1. Lag fuse construction comprising dual fuse elements of the instantaneous and delayed action types, said elements being in series, said delayed action type element including a pair of relatively

massive conductors of heat and electricity arranged in spaced relation, a movable conductive bridge carried by one of said massive conductors, an insulative bridge carried by the other of said massive conductors, said conductive and insulative bridge means being mutually displaceable across the space between said massive conductors, means pushing said insulative bridge against said conductive bridge to urge the latter out of bridging relation across said space, and fusible means connecting said conductive bridge to at least one of said massive conductors resisting said displacement.

2. The invention of claim 1, said conductive and insulative bridge means being coaxially aligned with each other and with said massive conductors, each bridge being telescopically interfitted with its respective conductor so as to alternately retract into and project outwardly therefrom.

3. The invention of claim 2, said pushing means being a compression spring disposed in the conductor within which said insulative bridge is retractible, said spring bearing against said insulative bridge and forcing it to butt against said conductive bridge.

4. The invention of claim 1, said fusible means comprising eutectic solder having a predetermined metal point.

5. Fuse construction having instantaneous and lag type fuses in series, said lag type fuse comprising a pair of massive metal members arranged in spaced relation, said members having bores coaxially arranged with respect to each other, a metallic plunger mounted in one of said bores and projecting therefrom across to the opposed member against which it is held by fusible material, and a compression spring and an insulative plunger mounted in the other of said bores, said insulative plunger being confined against the tension of said spring in said other bore by said metallic plunger with the parts in closed circuit position.

6. The invention of claim 5, the outer end of said metallic plunger having a contact head thereon larger than either of the bores in said metal members and against which said insulative plunger butts, and a complementary contact bearing for the contact head on said metallic plunger confronting the latter on the opposed metal member.

7. The invention of claim 6, in which said complementary contact bearing is countersunk in said opposed member in relation to the bore thereof.

8. The invention of claim 5 further characterized by the fact that when the parts are in open circuit position the metallic plunger is pushed into retracted position within its massive metal member by said insulative plunger, which in turn is projected by the expansive force of the spring from the bore of its massive metal member with which it is confined when the parts are in closed circuit position, to displace the metallic plunger from bridging relation between said members, and to hold the metallic member positively in open circuit position.

9. The invention of claim 8, said lag type fuse parts being enclosed in the middle chamber of a three-compartment fuse casing, the end chambers of which accommodate the instantaneous type fuses in series therewith.

10. The invention of claim 9, said casing having terminals thereon in which the instantaneous fuses terminate, the end chambers of said casing surrounding said instantaneous fuses being filled with quenching powder.

GORDON F. LAING.
